TETRAKISAZO DYESTUFFS SOLUBLE IN
WATER

Adolf Sieglitz and Martin Reuter, Frankfort-on-the-Main, Germany, assignors to General Aniline & Film Corporation, New York, N. Y., a corporation of Delaware

No Drawing. Application November 14, 1940, Serial No. 365,653. In Germany December 9, 1939

5 Claims. (Cl. 260—166)

The present invention relates to tetrakis-azo-dyestuffs soluble in water; more particularly it relates to the dyestuffs of the following general formula:

wherein X stands for a simple carbon linkage or for one of the groupings $-\text{CH}=\text{CH}-$ and $-\text{NHCONH}-$, and wherein the benzene nuclei may contain further substituents and at least one of the benzene nuclei a and b contains one or more sulfonic acid or carboxylic acid groups.

We have found that valuable tetrakis-azo-dyestuffs are obtained by coupling the tetrazo-compound from a diamine of the general formula:

wherein X stands for a simple carbon linkage or for one of the groupings $-\text{CH}=\text{CH}-$ and $-\text{NHCONH}-$, and wherein the benzene nuclei may contain further substituents, with the same or a different aceto-acetyl compound of the general formula:

wherein the benzene nuclei may contain substituents and at least one of the two benzene nuclei contains one or more sulfonic acid or carboxylic acid groups.

The dyestuffs which are derived from the di-

amino-diphenyl-urea-disulfonic acid as tetrazo-component may also be prepared by transforming the disazo-dyestuffs from mono-diazotized 1,4-diamino-benzene-sulfonic acid or the derivatives thereof and the aceto-acetyl compounds of the composition indicated above in known manner into the ureas, or by reducing the azo-dyestuffs from diazotized 4-nitro-1-aminobenzene-sulfonic acid or the derivatives thereof and the aceto-acetyl compounds named and transforming the amino-compounds obtained into the ureas.

The dyestuffs thus obtained are distinguished by a very good affinity for cotton fibers and regenerated cellulose fibers as well as for mixtures of these fibers and yield yellow and orange dye-

ings of very good fastness to water and to washing.

15 The aceto-acetyl compounds used as coupling components may be obtained by causing the corresponding amino-azo-compounds to react with diketene.

15 The following examples serve to illustrate the invention, but they are not intended to limit it thereto; the parts are by weight:

20 1. 402 parts of 4,4'-diaminodiphenylurea-3,3'-disulfonic acid are tertotized in the usual manner. The suspension of the tetrazo-compound is then introduced into a solution of 766 parts of the sodium salt of 4-acetoacetylamo-1,1'-azobenzene-4'-sulfonic acid (obtainable by causing diketene to act upon 4-amino-1,1'-azobenzene-4'-sulfonic acid) and 216 parts of sodium carbonate in water. When the coupling is finished the dyestuff is salted out, filtered with suction and dried. It is a yellow powder which has a very good affinity for cotton and viscose silk. The yellow dyeings obtained are distinguished by a very good fastness to water and to washing and a good fastness to light. A mixed fabric consisting of 50 parts of cotton and 50 parts of staple fiber from viscose is dyed yellow tone-in-tone tints. The dyestuff corresponds with the following formula:

45 The same dyestuff may be obtained by diazotizing 436 parts of 4-nitro-1-aminobenzene-2-sulfonic acid in the usual manner, coupling the diazo-compound obtained with 766 parts of 4-acetoacetylamo-1,1'-azobenzene-4'-sulfonic acid in a solution rendered alkaline with sodium carbonate, reducing in the usual manner the disazo-dyestuff obtained and transforming the amino-compound obtained with phosgene into urea.

50 The same dyestuff may be prepared by mono-diazotizing 376 parts of 1,4-diaminobenzenesul-

fonic acid in the usual manner, combining the diazo-compound with 766 parts of 4-aceto-acetyl-amino-1.1'-azobenzene-4'-sulfonic acid in a solution rendered alkaline with sodium carbonate and transforming the disazo-dyestuff thus obtained with phosgene into urea.

2. 402 parts of 4.4'-diaminodiphenylurea-3.3'-disulfonic acid are tetrazotized in the usual manner and the tetrazo-compound is introduced into an aqueous solution of 854 parts of the sodium salt of 4-acetoacetylarnino-2-methoxy-4'-methyl-1.1'-azobenzene-3'-sulfonic acid and 212 parts of sodium carbonate. The dyestuff obtained is salted out, filtered with suction and dried. It dyes cotton reddish-yellow tints of very good fastness to water and to washing and good fastness to light.

Dyestuffs of similar properties are obtained if the acetoacetyl compounds used in the preceding examples are replaced by

4-acetoacetylarnino-2.3-dimethyl-1.1'-azobenzene-4'.5-disulfonic acid,
4-acetoacetylarnino-2-methyl-2'-chloro-1.1'-azobenzene-5'-sulfonic acid,
4-acetoacetylarnino-2.2.5-trimethoxy-1.1'-azobenzene-5'-sulfonic acid or
4-acetoacetylarnino-1.1'-azobenzene-3'-carboxylic acid.

3. 344 parts of 4.4'-diaminodiphenyl-3.3'-disulfonic acid are tetrazotized in the usual man-

5. 344 parts of 4.4'-diaminodiphenyl-3.3'-disulfonic acid are tetrazotized in the usual manner. An aqueous solution of 338 parts of the sodium salt of 4-acetoacetylarnino-1.1'-azobenzene-4'-sulfonic acid is caused to run into the suspension of the tetrazo-compound and the solution is neutralized until a feebly acid reaction is produced. The disazo-dyestuff obtained is then coupled with 427 parts of sodium 4-acetoacetylarnino-2-methoxy-4'-methyl-1.1'-azobenzene-3'-sulfonate in a solution rendered alkaline with sodium carbonate. The tetrakisazo-dyestuff obtained dyes cotton reddish yellow tints of very good fastness to water and to washing.

15. 462 parts of 4.4'-diamino-2.2'-dimethoxy-diphenylurea-5.5'-disulfonic acid are tetrazotized in the usual manner and coupled with 766 parts of the sodium salt of 4-acetoacetylarnino-1.1'-azobenzene-4'-sulfonic acid in a solution rendered alkaline with sodium carbonate. The dyestuff obtained is an orange powder which dyes cotton reddish-yellow tints of good fastness to wet-processing.

20. Dyestuffs of similar properties are obtained by using 4-acetoacetylarnino-2-methyl-2'-chloro-1.1'-azobenzene-5'-sulfonic acid or 4-acetoacetylarnino-2-methoxy-4'-methyl-1.1'-azobenzene-3'-sulfonic acid as coupling component.

We claim:

1. The water-soluble tetrakis-azodyestuffs of the following general formula:

ner. The suspension of the tetrazo-compound is then introduced into 766 parts of the sodium salt of 4-acetoacetylarnino-1.1'-azobenzene-4'-sulfonic acid in a solution rendered alkaline with sodium carbonate. The dyestuff is separated by salting out, filtered with suction and dried. It dyes cotton reddish yellow tints of very good fastness to water and to washing and good fastness to light.

By using as coupling components 4-acetoacetylarnino-2-methoxy-4'-methyl-1.1'-azobenzene-3'-sulfonic acid or 4-acetoacetylarnino-2.3-dimethyl-1.1'-azobenzene-4'.5-disulfonic acid instead of 4-acetoacetylarnino-1.1'-azobenzene-4'-sulfonic acid or as diazo-component 4.4'-diamino-5.5'-dimethyl-diphenyl-3.3'-disulfonic acid dyestuffs of similar properties are obtained.

4. 370 parts of 4.4'-diaminostilbene-2.2'-disul-

5. 45 of hydrogen, methyl and alkoxy, Z1 stands for a member of the group consisting of the sulfonic acid and carboxylic acid groups, Z2 stands for a member of the group consisting of hydrogen, the sulfonic acid and carboxylic acid group, and Z3 and Z4 stand for members of the group consisting of hydrogen, methyl, alkoxy and chlorine groups, being yellow to orange powders which have a very good affinity for cotton, regenerated cellulose fibers and mixtures thereof and yield yellow and orange dyeings of very good fastness to water and to washing and good fastness to light.

2. The water-soluble tetrakis-azodyestuffs of the following general formula:

fonic acid are tetrazotized in the usual manner and coupled with 766 parts of the sodium salt of 4-acetoacetylarnino-1.1'-azobenzene-4'-sulfonic acid in a solution rendered alkaline with sodium carbonate. The dyestuff obtained dyes cotton orange tints of very good fastness to water and to washing.

A similar dyestuff is obtained by using 4-acetoacetylarnino-1.1'-azobenzene-3'-carboxylic acid as coupling component.

70. 75. wherein X stands for a member of the group consisting of a simple carbon linkage, the group -CH=CH- and the group -NHCONH-, being yellow to orange powders which have a very good affinity for cotton, regenerated cellulose fibers and mixtures thereof and yield yellow and orange dyeings of very good fastness to water and to washing and good fastness to light.

3. The water-soluble tetrakis-azodyestuff of the following formula:

being a yellow powder which has a very good affinity for cotton, regenerated cellulose fibers

dyeings of very good fastness to water and to washing and good fastness to light.

5. The water-soluble tetrakis-azodyestuff of the following formula:

and mixtures thereof and yields yellow dyeings of very good fastness to water and to washing and good fastness to light.

being an orange powder which has a very good affinity for cotton, regenerated cellulose fibers and mixtures thereof and yields orange dyeings

4. The water-soluble tetrakis-azodyestuff of the following formula:

being a yellow powder which has a very good affinity for cotton, regenerated cellulose fibers and mixtures thereof and yields reddish yellow

of very good fastness to water and to washing and good fastness to light.

ADOLF SIEGLITZ.
MARTIN REUTER.
